(57) **CLAIM**

The ornamental design for a hand vacuum, as shown and described.

DESCRIPTION

FIG. 1 is a front perspective view of a hand vacuum showing my new design;

FIG. 2 is a rear perspective view thereof;

FIG. 3 is a right side elevational view thereof;

FIG. 4 is a left side elevational view thereof;

FIG. 5 is a front end view thereof;

FIG. 6 is a rear end view thereof;

FIG. 7 is a top view thereof;

FIG. 8 is a bottom view thereof;

FIG. 9 is a second embodiment thereof;

FIG. 10 is a rear perspective view thereof;

FIG. 11 is a right side elevational view thereof;

FIG. 12 is a left side elevational view thereof;

FIG. 13 is a front end view thereof;

FIG. 14 is a rear end view thereof;

FIG. 15 is a top view thereof; and,

FIG. 16 is a bottom view thereof.

The broken line shown in FIG. 10 is for illustrative purposes only and forms no part of the claimed design.
